UNITED STATES PATENT OFFICE.

CHARLES J. ARNOLD AND WILLIAM PAYNE RUTHERFORD, OF LOUISVILLE,
KENTUCKY.

AUTOMATIC SMOKE-PREVENTER.

Specification of Letters Patent.

Patented Dec. 28, 1915.

1,166,307.

Application filed October 13, 1914. Serial No. 866,521.

To all whom it may concern:

Be it known that we, CHARLES J. ARNOLD and WILLIAM P. RUTHERFORD, citizens of the United States, residing at Louisville, in the county of Jefferson and State of Kentucky, have invented new and useful Improvements in Automatic Smoke-Preventers, of which the following is a specification.

10 The invention relates to a boiler furnace attachment, and more especially to the class of automatic smoke preventive devices for boiler or other furnaces.

The primary object of the invention is 15 the provision of a device of this character wherein on the opening of the doors to the fire boxes of the boiler furnace steam will be admitted to the fire boxes to prevent the smoking of the fire and on the closing of the said doors the steam will be automatically and gradually shut off from the fire boxes of the furnace, thereby preventing the smoking of the said furnace.

Another object of the invention is the 20 provision of a device of this character which is novel in form to insure the automatic working thereof with certainty for preventing the smoking of the fire of a furnace.

A further object of the invention is the 25 provision of a device of this character which is simple in construction, automatic in operation, reliable and efficient in its purpose and inexpensive in manufacture and

Similar reference characters indicate corresponding parts throughout the several views in the drawing.

Referring to the drawing in detail, A designates generally the front of a boiler 60 furnace of the usual well known construction, B the fire box doors, C the ash pit doors and D the steam supply pipe leading from the boiler of the said furnace, the said pipe 65 D being fitted with respective globe and butterfly valves E and F, the latter having connected to its stem an arm or lever G which is operated by means of the device herein-after fully described.

Connected to the steam supply pipe D is a 70 cross branch pipe 10, to which are connected steam jets 11, the latter being extended through the front wall of the furnace into the fire chambers therein so that steam may be supplied through the jets 11 thereinto. 75

The device comprises clock mechanism including a frame 12, which is bolted or otherwise fastened to the front wall A of the furnace at one side of the doors thereon and within this frame is journaled an arbor 13, 80 to which are fixed the respective rocker arm gear 14 and 8-toothed gear 15, the latter meshing with a 72-toothed gear 16 fixed to a shaft 17 journaled in the said frame 12, 85 which has fixed thereto a 24-toothed ratchet gear 18 and an 8-toothed sprocket gear 19, while pivotally connected at diametrically opposite points on one face of the gear 23

Dear Dr. G. C. Shantz,
I am sending you a copy of the paper I have written on the
leeches of the Lake Ontario region.

It is a short paper, and I hope you will like it. I have not
had time to get it through the printer, so I am sending you
a copy of the manuscript.

I have also sent you a copy of the paper I have written on the
leeches of the Lake Ontario region.

I hope you will like it. I have not had time to get it through
the printer, so I am sending you a copy of the manuscript.

I have also sent you a copy of the paper I have written on the
leeches of the Lake Ontario region.

I hope you will like it. I have not had time to get it through
the printer, so I am sending you a copy of the manuscript.

I have also sent you a copy of the paper I have written on the
leeches of the Lake Ontario region.

I hope you will like it. I have not had time to get it through
the printer, so I am sending you a copy of the manuscript.

I have also sent you a copy of the paper I have written on the
leeches of the Lake Ontario region.

I hope you will like it. I have not had time to get it through
the printer, so I am sending you a copy of the manuscript.

I have also sent you a copy of the paper I have written on the
leeches of the Lake Ontario region.

I hope you will like it. I have not had time to get it through
the printer, so I am sending you a copy of the manuscript.

I have also sent you a copy of the paper I have written on the
leeches of the Lake Ontario region.
